UNITED STATES PATENT OFFICE.

LANE JOHNSON, OF INGRAM, PENNSYLVANIA, ASSIGNOR TO UNITED ENGINEERING & FOUNDRY COMPANY, OF PITTSBURGH, PENNSYLVANIA, A CORPORATION OF PENNSYLVANIA.

REPEATER FOR ROLLING MILLS.

Application filed September 29, 1924. Serial No. 740,530.

The present invention relates to repeaters for rolling mills, and particularly to repeaters for rolling oval shapes. The purpose of the invention is to provide power means 5 for forcing the leading end of a bar through the fixed guide associated with the intermediate or finishing rolls. Heretofore this has been accomplished by having a workman stand at the guide and open the same 10 by means of a wrench to permit the leading end of each bar to pass through the guide and be gripped by the intermediate or finishing rolls, after which the guide was tightened up. By the present invention this manual operation is eliminated.

A preferred embodiment of the invention is illustrated in the accompanying drawings, in which:

Figure 1 is a plan view, partly diagrammatic, of a repeater embodying my invention;

Figure 2 is a view, partly in section and partly in elevation, of the means for twisting the bars;

Figure 3 is a section on the line III—III of Figure 2;

Figure 4 is a vertical section through the finishing or intermediate rolls, the fixed guide and the power means for pushing the bars through the guide; and

Figure 5 is a section on the line V—V of Figure 4.

Referring to Figure 1, the reference numerals 2 and 3 designate a pair of rolling mills and 4 a repeater associated therewith. The rolls of the rolling mill 2 have an oval pass 5 for rolling a square bar into an oval shape.

Interposed between the receiving end of 40 the repeater and the rolling mill 2 is a twister T. This twister comprises a pair of parallel vertical guides 6, having T-shaped slots 7 therein. Adjustably mounted on the guide 6 is a support 8 held in adjusted position 45 by bolts 9 having T heads engaging in the slots 7 in the guides. Rotatably mounted in the support is a housing 10, having a worm gear 11, on its periphery. This housing is adapted to be rotated by means of a worm 50 12, journaled in the support. The housing has mounted therein a pair of cooperating rolls 13 and 14, the rolls being journaled in movable bearings 15, against which coil springs 16 act. These springs tend to move

the rolls 13 and 14 towards each other. The 55 rolls 13 and 14 have an oval pass 17. In operation, the housing 10 is turned so that the axes of the rolls 13 and 14 have a slight angle to the horizontal. The end of the bar after it leaves the horizontal pass 5 of the 60 rolling mill 2 is received in the pass 17 of the rolls 13 and 14 and is given a slight twist. The length of the repeater 4 is such that by the time the end of the bar reaches the fixed guide 18 associated with the intermediate or finishing rolls 3, the end of the bar has been turned through an angle of 90° 65 so that the oval section has its axis vertical. The rolls of the rolling mill 3 have a round or square pass 19, to receive the bar and the 70 guide 18 has a pass 20, which fits closely around the entering bar. Interposed between the guide 18 and the delivery end of the repeater is a pair of vertical rolls 21 having a vertical oval pass 22. These rolls 75 are mounted on vertical shafts 23 having pinions 24 at their upper ends which mesh with each other. One of the shafts 23 has a bevel pinion 25 at its upper end which is engaged by a bevel pinion 26 on a shaft 27. 80 The shaft 27 is adapted to be driven by any suitable means through a ratchet clutch 28.

The vertical rolls 21 are driven at a slightly less peripheral speed than the rolls of the rolling mill 3. The leading end of a bar 85 enters the pass 22 of the rolls 21 and the end of the bar is pushed through the pass of the guide 18 until the end of the bar is received in the pass 19 of the rolling mill 3. As soon as the rolls of the rolling mill 3 grip the end 90 of the bar, they draw the bar through the guide 18 at a greater lineal speed than the normal peripheral speed of the rolls 21, so that the latter are rotated by the bar at a greater peripheral speed than that at which 95 the shaft 27 tends to drive them, this being permitted by the ratchet clutch 28. In other words, as soon as the rolls of the rolling mill 3 grip the bar, the rolls 21 cease to function. The purpose of these rolls, as before stated, 100 is merely to push the end of the bar through the guide 18 until it is gripped by the rolls of the rolling mill 3.

The rolls 21 have the usual springs 29 associated therewith for yieldingly holding 105 the rolls in contact with each other.

While I have shown and described a preferred embodiment of my invention, it will

be understood that changes may be made in the details of construction without departing from the spirit of the invention or scope of the appended claims.

5 I claim:

1. In a repeater for rolling mills, a repeater, a rolling mill adjacent the delivery end of said repeater, a guide associated with said rolling mill for guiding the end of a 10 bar from the delivery end of said repeater into the pass of said mill, a pair of driven rolls interposed between the delivery end of the repeater and said guide for pushing the end of the bar through said guide, means 15 for driving said rolls at a smaller peripheral speed than that of the rolls of the rolling mill, and means in the driving connections of said rolls whereby the rolls are driven by the bar after the latter has been gripped 20 by the rolls of said rolling mill, substantially as described.

2. In a repeater for rolling mills, a repeater, a rolling mill adjacent the receiving end of said repeater, a rolling mill adjacent 25 the delivery end of said repeater, a twister interposed between said rolling mill and said receiving end of the repeater, a rolling mill adjacent the delivery end of said repeater, a guide associated with said rolling mill 30 for guiding the end of a bar from the delivery end of said repeater into the pass of said mill, and means interposed between the delivery end of the repeater and said guide

for forcing the end of the bar through said guide, substantially as described.

3. The combination with a pair of rolling units, of a repeater guide through which a rod emerging from one unit is directed to the pass in the other unit, and a twister interposed between the first roll and the guide through which a rod emerging from the first rolling unit must pass and by means of which the rod is turned the necessary amount to be received by the pass of the second unit, and a feeding means at the other end of the repeater guide between its terminal and the second rolling unit, said guide having a pass therethrough conforming to the pass in the second rolling unit and positioned to receive the end of a rod moving through the guide at the angle imparted thereto by the twister.

4. The combination with a pair of rolling units, of a repeater guide through which a rod emerging from one unit is directed to the pass in the other unit, and a twister interposed between the first unit and the guide, said twister having a pair of rollers therein with a pass therebetween, the pass in the twister rollers being at an angle to the pass in the first rolling unit and means for resiliently supporting and urging each of the rollers in the twister toward the other.

In testimony whereof I have hereunto set my hand.

LANE JOHNSON.
